CLAIM

The ornamental design for a vehicle door as shown and described.

DESCRIPTION

FIG. 1 is a front-right corner perspective view of a vehicle door showing the claimed design;

FIG. 2 is a right-side view of the vehicle door; and, FIG. 3 is a rear-right corner perspective view of the vehicle door.

Features of the vehicle rendered in broken lines surrounding the vehicle door, and the two regions bounded in broken lines within the vehicle door, form no part of the claimed design, and the dashed-dot line shows a boundary of the unclaimed portion of the vehicle and forms no part of the claimed design.
